Primary Examiner — Sandra S Snapp*Assistant Examiner* — Mehri Bajoul(74) *Attorney, Agent, or Firm* — Hanrahan Law Firm
P.A.; Benjamin M. Hanrahan(57) **CLAIM**

The ornamental design for a sports training net, as shown and described.

DESCRIPTION

FIG. 1 is a front perspective view of a sports training net showing our new design.

FIG. 2 is a rear perspective view thereof.

FIG. 3 is a right-side view thereof.

FIG. 4 is a front view thereof.

FIG. 5 is a left-side view thereof.

FIG. 6 is a rear view thereof.

FIG. 7 is a top view thereof; and,

FIG. 8 is a bottom view thereof.

(Continued)

The broken lines in the drawings depict portions of the sports training net that form part of the claimed design.

1 Claim, 8 Drawing Sheets
